N. C. FLANNERY

APRON

Filed Sept. 15, 1921

FIG. 1.

FIG. 2.

FIG. 2.

Inventor:
Nelle C. Flannery,
By Doran & Stark, Atty

Patented Apr. 1, 1924.

1,488,635

UNITED STATES PATENT OFFICE.

NELLE C. FLANNERY, OF WOOSTER, OHIO.

APRON.

Application filed September 15, 1921. Serial No. 500,968.

To all whom it may concern:

Be it known that I, NELLE C. FLANNERY, a citizen of the United States, residing at Wooster, in the county of Wayne and State 5 of Ohio, have invented a new and useful Apron, of which the following is a specification.

My invention relates to improvements in aprons; and particularly to the class adapted to the use of operatives in beauty culture work, seamstresses, nurses, and the like; and its principal objects are to provide a neat, convenient, serviceable and easily made apron garment for such uses, and 15 which has the superior advantages herein-after set forth. It consists of the novel arrangement and combination of elements herein described, and as stated in the appended claims.

20 My invention is illustrated by the accompanying drawings, in which similar letters and figures of reference indicate like parts.

Referring thereto, Fig. 1 is a front view of an apron embodying my invention; Fig. 2 is a detail view of the back, side, and front sections extended flatwise; one side of the front section, which is in all respects similar to the other, is cut away as superfluous; Fig. 3 is a detail view of the front, 30 and one side section of the apron, detached, a portion of the front section being cut away for better illustration of the extension of the side section.

In the drawings, A is the front, B, the 35 back, and C, the side sections, respectively, of my improved apron, the side sections being right and left duplicates of each other, only one need be referred to for description.

40 D D are pockets, and E E, the belt sections for the apron, and F F, the sleeves; the latter are similar to sleeves heretofore used, and may be shaped to suit the taste, and as no claim is specifically made there- 45 to, further statement concerning them will be omitted.

Heretofore aprons have been generally made either of a single front member, or of a front and back member joined together, 50 and are as common as they are shapeless; and pockets have been sewed thereon in various ways, and belts have been attached thereto to suit the plan.

I am also aware it is not new to construct 55 a garment with an upwardly extended flap in front over the waist thereof, and that

skirt fronts have been notched to provide pockets therein, and such I do not broadly claim.

My improvement relates more particularly to the method of constructing and combining the front section A and opposite side sections C C, whereby a panel front a is provided as an upward extension of the front section A, the lower or skirt portion of said front section being extended laterally in both directions to the back section and united thereto by seams s, s' in such manner as to overlap the extended lower ends of the side sections C, 70 C, respectively. The latter extend some distance below the upper margins of said lateral extensions where they connect by a seam, leaving said upper margins disconnected; and the margins of said side sections adjacent the panel front are united thereto, either solidly or detachably, as 75 may be preferred for convenience.

By this arrangement the panel front a gives shape to the apron when put on, and 80 causes it to hang well upon a form. The belt E is preferably made in two parts, each sewed upon opposite edges of the panel a, and their loose ends adapted to be fastened together at the back of the apron in 85 any desired manner. Pockets D D are constructed by extending the side sections C C down behind the upper part of the lateral extensions a', a', a sufficient distance for 90 depth, and there stitching them together as aforesaid. The junction of the side section C with the panel front is best shown in Fig. 3, wherein the front portion of the pocket is cut away so as to show the location of the bottom of said side section at 95 c', and its attachment along the dotted lines 1—2—3. The panel front a, being detachably secured to the adjacent edge of the side section C as shown at a², provides 100 a convenient means for adjusting the apron, but no claim is herein made to this feature, except in combination with the novel construction aforesaid.

It is apparent that by the construction aforesaid, no extra material is required, 105 nor any folding of parts for pockets, and that the apron is completed by simply sewing the back and front sections together and inserting the side sections in the manner indicated in Fig. 2 by the several seams, s', s², s³. The arrangement of the pockets is 110 such that when the belt E is drawn around

the body of a person, there is a convenient extension of the outer member of the pocket, and the co-operation of the panel section and belt make the garment more shape-
• 5 ly than has been heretofore possible. More-
over, said pockets are less liable to wear
and tear, and are simpler and neater than
if sewed on the outside of the garment or
formed in cut away sections of the skirt as
10 heretofore.

15 Collar and cuffs may be added to the
apron, at pleasure, and size and shape of
the several parts may be modified to suit
the taste or needs of the wearer of the
apron.

Having thus fully described my inven-
tion, what I claim as new and desire to
secure by Letters Patent is—

1. In a garment of the character de-
scribed, the combination of a back section,
comprising waist and skirt portions in one
piece, a front section comprising waist and
skirt portions in one piece, the upper or
waist portion of the front section extend-
ing upwardly from the lower portion of
25 said section as a panel front, and the lower
portion extended laterally in both direc-
tions to engage the adjacent longitudinal
margins of the back section, and a
right and left pair of side sections
30 intermediate the back section and the upper
portion of the front section, on opposite

sides thereof, said side sections being ex-
tended downwardly some distance below the
upper margins of the lateral extensions of 35
the front section, respectively, underneath
said extensions, and seams uniting said side
sections, respectively to the back and front
sections accordingly, substantially as set
forth. 40

2. An apron garment, comprising, in com-
bination, a back section, a front section
having a panel extension at its top, and
lateral extensions below said panel, a right
and left pair of side sections intermediate 45
the sides of said panel and the adjacent
edges of said back section, said side sec-
tions extending some distance below said
panel, and underneath the lateral extensions
of said front section, respectively, and 50
seamed thereto; and a belt connecting the
opposite sides of said panel, and adapted
to surround said side and back sections;
and the upper margins of said lateral ex-
tensions being disconnected from said ad-
jacent side sections for some distance, sub-
stantially as set forth and for the purpose
specified. 55

In witness whereof, I hereunto set my
hand this 23 day of May, 1921.

NELLE C. FLANNERY.

In presence of—

HIRAM B. SWARTZ,
JOHN C. McCALARAN.
